(57) **CLAIM**

The ornamental design for a wireless remote, as shown and described.

DESCRIPTION

The following commonly-assigned patent applications have at least some subject matter in common with the current application:

Ser. No. 13/250,642 entitled "First Emergency Response Device", filed Sep. 30, 2011.

FIG. 1 is a perspective view of our design comprising a wireless remote;

FIG. 2 is a top view of our design of my wireless remote;

FIG. 3 is a bottom view of our wireless remote;

FIG. 4 is a right side view of our wireless remote;

FIG. 5 is a left side view of our wireless remote;

FIG. 6 is a bottom end view of our wireless remote; and,

FIG. 7 is a top end view of our wireless remote.

All other surface(s) or portion(s) of the embodiments of our design not shown in the figures or otherwise described in the specification form no part of the claimed design.

1 Claim, 7 Drawing Sheets
